J. WASHUK

CONCEALED TROUSER SUPPORTING BELT

Original Filed April 15, 1922

Patented July 22, 1924.

1,502,414

UNITED STATES PATENT OFFICE.

JOHN WASHUK, OF DETROIT, MICHIGAN.

CONCEALED TROUSER-SUPPORTING BELT.

Application filed April 15, 1922, Serial No. 552,953. Renewed May 5, 1924.

To all whom it may concern:

Be it known that I, JOHN WASHUK, a citizen of Russia, residing at Detroit, in the county of Wayne and State of Michigan, 5 have invented certain new and useful Improvements in Concealed Trouser-Supporting Belts, of which the following is a specification.

This invention relates to a belt intended 10 more particularly for use in supporting men's trousers, having especial reference to a belt arranged to support the trousers, without undesirable compression of the waist of the user, by transferring the weight to 15 the hips of the user.

The invention has for an object to provide a novel and improved belt of the above type, which is concealed from view.

For further comprehension of the invention, and of the objects and advantages thereof, reference will be had to the following description and accompanying drawings, and to the appended claims in which the various novel features of the invention 25 are more particularly set forth.

Fig. 1 of the drawings is a front elevational view indicating my improved belt as in actual use.

Fig. 2 is a face view of the belt extended. 30 Fig. 3 is an enlarged transverse vertical section on the line 3—3 of Fig. 2, indicating also a portion of the trousers supported by the belt.

Fig. 4 is a longitudinal section on the line 4—4 of Fig. 2.

Fig. 5 is a transverse vertical sectional view showing the means for varying the width of the belt, this view being taken on the line 5—5 of Fig. 6.

40 Fig. 6 is an enlarged fragmentary longitudinal sectional view taken on the line 6—6 of Fig. 5.

Fig. 7 is a detail face view of the adjustable stay.

45 As here shown my improved belt comprises outer and inner layers of flexible material numbered respectively 10 and 11, between which are located the vertically extending stiffening members or stays, which 50 are indicated generally at 12 in Figs. 2 and 4. These latter are preferably formed of spring steel so as to have resiliency, while the cloth elements 10 and 11 may be formed of canvas, drill, or other cloth, or of leather 55 or any suitable material. The stays 12 are arranged in pairs, as shown, suitably spaced

along the belt, which is of considerably greater vertical dimension than an ordinary trouser belt. The bottom edges of the elements 10 and 11 are secured together by 60 stitching, the edge of one of the members being here shown as turned back over the other as at 13.

The stays 12 may be localized in the belt by means of the adjacent vertical rows of 65 stitches 15 extending through the two parts 10 and 11.

To secure the belt in position the ends thereof are here shown as provided with the rows of eyelets 18 through which a cord 19 70 may be laced.

On the inner side of the belt, at the back thereof, I provide a pad 20, which may comprise a facing strip secured over a filling element 20' of cotton, this pad resting 75 against the base of the spine and the adjacent pelvic bones and preventing irritation thereof. My improved belt in addition to serving as a support for the trousers may also be used as a money belt and to this end 80 I provide on the outer face thereof a pair of pockets 21 closed at their upper ends by flaps 22.

In Figs. 5, 6 and 7 I have shown in detail the means for varying the width of the belt. 85 As here shown each stay is formed in two sections 12', and 12^a respectively. The section 12^a has a series of horizontal slots 30 therein while, the section 12' is formed with notches 31 at each side adjacent the end. 90 These notches are of such a depth as to leave the neck between them of sufficiently smaller lateral dimension than the slots 30 to permit of engagement and disengagement of the ends of the stay sections by an initial lateral movement of one section on the other. This lateral movement is prevented by the lines of stitching which localize the stays in the belt and which form pockets in which the stays are removably seated. These pockets 95 are closed at their upper ends by a flap 33 formed on and extending the full length of one of the the belt elements 10, 11, (as here shown the inner element 11) and which folds over the other element as in Fig. 2, 100 this flap 33 having suitable series of hooks such as 34 along its edge adapted to engage any corresponding ones of a number of vertically spaced eyes 35 on the other element. Suitably attached to this flap 33 are a number of hooks 17 to which the trousers, indicated at 25, are attached, the trousers hav-

105
110

ing suitable eyes on the inner surface of the waistband which engage these hooks. In use the belt is worn under the shirt, indicated at 24, of the user which is formed with 5 suitable slots through which the hooks 17 are projected.

The width of the belt, which may be varied as desired, is sufficient to enable it to rest on the hips of the wearer, while at the 10 same time supporting the trousers in normal position and preventing undesirable sagging of the latter. As will be apparent, the belt is entirely concealed and no visible evidence 15 is present of its use, while an ordinary belt may be worn on the trousers in the usual manner if desired.

Having thus described my invention what I claim as new and desire to protect by Letters Patent of the United States is as follows:

- 20 1. A concealed trouser supporting belt comprising a fabric formed with pockets, stays in said pockets adjustable in length, a flap extending along the upper edge of said fabric and adapted to be folded over the tops of the said stays, and means for securing the said flap to the body of the fabric in vertically adjusted positions, for the purpose specified.
- 25 2. In a device of the class described, a belt element, adjustable stays therefor, said stays each comprising upper and lower sections overlapping one another, one section being formed with a series of longitudinally spaced and transversely extending slots, the other section being notched on opposite sides

40 adjacent its end, the said notches being of sufficient depth to permit of insertion of the extreme end of the said other section in any of the said slots whereby the two sections are interlocked against relative vertical movement.

45 3. In a device of the class described, a belt element, adjustable stays therefor, said stays each comprising upper and lower sections overlapping one another, one section being formed with a series of longitudinally spaced and transversely extending slots, the other section being notched on opposite sides adjacent its end, the said notches being of 50 sufficient depth to permit of insertion of the extreme end of the said other section in any of the said slots whereby the two sections are interlocked against relative movement, and means on the belt element for preventing 55 relative transverse movement of the two sections.

4. A concealed trouser supporting belt, comprising a fabric member extensible in width, transverse pockets formed in said fabric member, and stays in said pockets adjustable in length.

5. A concealed trouser supporting belt, comprising a fabric member extensible in width, transverse pockets formed in said fabric member, and stays in said pockets adjustable in length, said stays being each formed in upper and lower sections interlocked at their meeting ends.

60 In testimony whereof I have affixed my signature.

JOHN WASHUK.
